UNITED STATES PATENT OFFICE.

ONESIME LADEBAUCHE, OF WOONSOCKET, RHODE ISLAND.

CAN-GILL GUIDE.

Application filed September 13, 1922. Serial No. 537,997.

To all whom it may concern:

Be it known that ONESIME LADEBAUCHE, residing at Woonsocket, in the county of Providence and State of Rhode Island, has invented new and useful Improvements in Can-Gill Guides, of which the following is a specification.

The object of the invention is to provide an improved worsted gill box or wool straightening or combing mechanism and more particularly to provide a thread guide for use in connection with conventional forms of gillboxes whereby the runs or mats of yarn are received from the drawing rolls and delivered to the calender rolls under conditions insuring the proper rolling or folding of the sheets of yarn for introduction into the can or for producing the worsted; and with this object in view the invention consists in a construction and combination of parts of which a preferred embodiment is shown in the accompanying drawings, wherein:—

Figure 1 is a sectional view of a can gill in which is incorporated a guide embodying the invention.

Figure 2 is a plan view of the guide detached.

Figure 3 is a detail view in perspective of the same.

Figure 4 is a vertical sectional view thereof.

Figures 5 and 6 are prospective views in different positions of the guide funnels or yarn rolling elements.

The machine in which the guide embodying the invention is illustrated includes a conveyor 10 of the endless type by which the sliver 11 is carried to the intake rolls 12, one of which as in the ordinary practice is under adjustable spring pressure for maintaining a yielding contact with the sliver, and also includes the fallers or combing means 13 which act upon the wool as it approaches the drawing rolls 14, the lower of which is traversed by the combing belt 15. Said machine also includes the calender rolls 16 and the usual cans 17 for receiving the worsted therefrom.

In substitution for the usual guide employed between the drawing rolls and the calender rolls there is arranged a guide shown in detail in Figure 3 of the drawing which embodies a transverse bar 18 disposed adjacent to the plane of the drawing

rolls and beneath which the sheet or sheets of wool forming the combed sliver pass said bar being adjustable toward and from the plane of the drawing rolls by means of the screw and slot connections 20 in the brackets 19 by which it is supported. The guide also embodies the folding guide funnels 22 mounted upon the supporting bar 21 and adapted to receive and roll inward the edges of the slivers so as to initiate the operation of forming the slivers into yarn. These folding guides are provided with flared mouths 23 and reduced throats 24 longitudinally split or slotted as indicated at 25 to afford a view of the yarn as it passes therethrough and the positions of the funnels may be varied on the supporting bar by means of the standards 26 which are provided with series of openings 27 for selective engagement by the securing bolts 28. The brackets 19 are also adjustable toward and from each other by reason of the slots 29 and bolts 30 and the supporting bar is adjustably engaged by means of the openings 31 and bolts 32 with brackets 33 which are slotted as shown at 34 for adjustment upon the frame 35.

Thus the position of the guiding bar 18 with relation to the drawing rolls, the positions of the folding guides or funnels with relation to the guide bar and also with relation to the plane of the calender rolls, and the position of the supporting bar with relation to the machine frame and hence with relation to both the calender and drawing rolls, may be varied to provide for a proper operation of the folding guides in rolling the slivers as they leave the drawing rolls and before they reach the calender rolls for discharging to the can to the end that a more efficient formation of the yarn may be insured.

Having described the invention, what is claimed as new and useful is:—

1. A guide attachment for worsted gill boxes adapted for interposition between the faller mechanism and the calender rolls, said attachment comprising a supporting bar for disposition in transverse relation to the path of the yarn, guide funnels adjustably mounted on said bar, angular brackets supporting said bar and provided with longitudinal slots in those arms for engagement with the machine to which the device is attached, said slotted arms providing for ad-

justment of the supporting bar and guide members toward and away from the faller mechanism and rolls.

2. A guide attachment for worsted gill boxes adapted for interposition between the faller mechanism and the calender rolls, the same comprising tubular throats having flared entrance mouths, said tubular throats being longitudinally split or slotted to provide an inspection opening for passing yarn.

3. A guide attachment for worsted gill boxes adapted for interposition between the faller mechanism and calender rolls, the same having guide funnels, and a transverse

bar disposed in advance of said guide funnels and below the plane of delivery from the faller mechanism.

4. A guide attachment for worsted gill boxes adapted for interposition between the faller mechanism and the calender rolls, the same comprising guide funnels, a transverse guide bar, and brackets supporting said bar and adjustable to move the bar toward and from the plane of the calender rolls.

In testimony whereof he affixes his signature.

ONESIME LADEBAUCHE.
